[57] CLAIM

The ornamental design for jacket or similar article, as shown and described.

DESCRIPTION

FIG. 1 is a front elevational view of a jacket or similar article showing my new design;

FIG. 2 is a rear elevational view thereof;

FIG. 3 is a front elevational view of another embodiment of a jacket or similar article showing my new design wherein the pockets are eliminated; and

FIG. 4 is a rear elevational view thereof showing the simplification of the rear ornamentation from the corresponding ornamentation on the FIGS. 1 and 2 embodiment.
